CLAIM

The ornamental design for the pump adapter, as shown and described.

DESCRIPTION

Cross-reference is made to U.S. Non-Provisional patent application Ser. No. 16/553,619, titled "Pump Adapter", filed on Aug. 28, 2019, all of which is expressly incorporated herein by reference.

FIG. 1 is a perspective view of a pump adapter shown with a clamp shown in broken line;

FIG. 2 is a perspective view of the pump adapter shown without the unclaimed clamp;

FIG. 3 is a lower perspective view of the pump adapter of FIG. 1;

FIG. 4 is a side elevational view of the pump adapter of FIG. 2;

FIG. 5 is an opposite side elevational view of the pump adapter of FIG. 2;

FIG. 6 is a front elevational view of the pump adapter of FIG. 2;

FIG. 7 is a rear elevational view of the pump adapter of FIG. 2;

FIG. 8 is a top plan view of the pump adapter of FIG. 2; and, FIG. 9 is a bottom plan view of the pump adapter of FIG. 2. The broken lines shown on the drawings form no part of the claimed design.
